UNITED STATES PATENT OFFICE

REUBEN ECKSTEIN, OF NEW YORK, N. Y.

PORTABLE ELECTRIC LIGHTING OUTFIT

Application filed January 7, 1929. Serial No. 330,774.

This invention relates to electric lighting sets. More particularly the invention is directed to portable lighting outfits for display and ornamental illumination such as used for interior, exterior, show windows and Christmas tree decorative lighting and other like purposes.

One object of the invention is to provide an improved electric lighting outfit construction in which the parts thereof may be sold separately and readily assembled in series or parallel circuit by even unskilled persons.

Another object of the invention is to provide in a portable lighting outfit of the character described, lamp sockets having improved solderless connection means for joining said sockets to the conductor wires, which shall permit varying the spacing and number of the sockets in circuit to suit the requirement of installation and also shall provide ready means for repositioning and rearranging the circuit parts from an original assembly.

A further object of the invention is to provide an improved portable lighting outfit of the character described comprising few and simple parts which shall be cheap to manufacture and practical and efficient to a high degree in use.

Other objects of this invention will in part be obvious and in part hereinafter pointed out.

Certain features herein shown and described are shown, described and claimed in my co-pending application Serial No. 323,116 filed Dec. 1, 1928.

The invention accordingly consists in the features of construction, combinations of elements and arrangement of parts which will be exemplified in the constructions hereinafter described and of which the scope of application will be indicated in the following claims.

In the accompanying drawings, in which is shown various possible illustrative embodiments of this invention,

Figs. 1 and 2 are front elevational views, partly diagrammatic, showing portable decorative lighting outfits with the lamp sock-

ets connected in series and parallel circuit, respectively, constructed to embody the invention.

Fig. 3 is a cross sectional view taken through one of the improved assembled lamp sockets showing interior construction.

Fig. 4 is a cross sectional view similar to Fig. 3 showing the parts separated ready for assembly.

Fig. 5 is a top plan view of the improved lamp socket showing with the cover member removed.

Figs. 6, 7 and 8 are fragmentary views showing various types of solderless connections of improved lamp socket terminals with conductor wires embodying the invention, and

Fig. 9 is a fragmentary cross-sectional view taken through another modified construction of the improved lamp socket.

Referring in detail to the drawings, 10 denotes decorative lighting outfits constructed to embody the invention which are seen to comprise a plurality of miniature lamp sockets 11 connected either in series or parallel circuit as shown in Figs. 1 and 2, respectively, by flexible conductors 12. The latter are preferably formed with a core of strand wires 12a having a suitable insulating covering 12b of any well understood construction.

The free ends of the circuit conductors 12 have applied thereto a plug cap 13 of any conventional make for attaching the outfit 10 to a suitable power supply (not shown) in the well understood manner.

A feature of the invention is the improved construction of said outfit whereby the lamp sockets can be interchanged, replaced, selectively spaced, and form separate, complete units which are easily and quickly assembled, said sockets being simple to connect in circuit without requiring a high degree of mechanical or electric skill. To this end, the current carrying parts of the sockets have terminals of improved construction novelly incorporated therewith for engaging and electrically connecting with the conductor wires whereby the sockets may be

positioned in any desired spaced relation to suit the requirement of the installation.

The socket 11 may comprise a suitable fibre or molded insulating casing 15 having a chamber 15c extending in from an open end 15a thereof, said casing being formed with a closed end wall 15b at the bottom of said chamber. Snugly fitted into the chamber 15c there is a metallic screw contact shell 17 which is adapted to receive the base of a miniature lamp, indicated at L in dotted lines. See Fig. 3.

The shell 17 at its inner end has a flange portion 17a against which abuts an insulated disc or washer 18. The shell 17, by means of the washer 18, is anchored to the casing wall 15b preferably by means of the screw 20 which extends centrally through said washer and wall.

Connected to or integrally formed with the shell flange portion 17a there is a flexible terminal 21 which extends through a wall passage 15c at a spaced distance from the screw 20.

A similar terminal 22 extends through another wall passage 15d, located on the opposite side of the screw 20 with respect to the wall passage 15c, to separate the terminals as much as possible. Said terminal 22

forms one end of a central current carrying member 23, the middle portion 23a of said member being adapted to lie between the washer 18 and the wall 15b and secured by the screw 20 as is clearly shown in Fig. 3.

The end of the member opposite the terminal 22 extends through the washer 18 and is bent to form the center spring contact 24 for the socket 11, the latter extending over the head 20a of the screw 20.

The exterior side of the casing wall 15b may be recessed as at 15e to receive the terminals 21 and 22 and a cover member 25 of fibre, molded or other suitable insulating material is provided for enclosing the live exposed terminal connections. The wall of said recess 15e may be formed with spaced communicating grooves 15f through which the conductor 12 extends.

Embedded centrally in the member 25, there is a nut 26 which is adapted to engage the threaded end 20b of the screw 20. In mounting the socket 11 in position on the conductors 12, the screw 20 engaging the nut 26 clamps the conductors 12 between the casing wall 15b and the member 25 as is readily understood from Fig. 3.

The practical application of the invention will now be apparent. With the sockets 11, conductors 12 and cap plug 13 constructed to form separate units as shown in the drawing, the outfit is assembled with the sockets selectively spaced along the conductors to suit the requirements of the installation.

Each socket is connected in circuit by simply removing a small portion of the in-

sulating covering 12b of the conductor so that the terminals 21 or 22 bend about the bared strand wires 12a electrically contact therewith. To insure positive electrical connection, a pin 27 may be provided for inserting through the bight 21a of the bent terminal 21 and in between the wire strands 12a as is clearly shown in Figs. 3 and 4. The cover member 25 is then applied for clamping the socket to the conductors, said member then encloses the live current carrying parts and also retains the pins 27 from becoming displaced.

It should be noted that in the improved outfit 10 the sockets 11 may thus readily be replaced, spaced in any desired uniform or un-uniform distance apart or interconnected in series or multiple circuits, any bare and exposed wire strands being taped in the well understood manner.

In Figs. 7 and 8 modified forms of socket terminals and connections are shown.

In Fig. 7, the terminal 121 comprises a bendable pointed prong. Said prong is preferably inserted into a passage pierced through the insulating covering 12b of a conductor for electrically contacting with the strand wires 12a. The prong is preferably made relatively wide to present a substantial large contact surface and when inserted with a bend 121a said terminal serves to anchor itself to the conductor.

The modification shown in Fig. 8 differs from that described above and shown in Fig. 7 in that the terminal 221 comprises a bendable double pointed prong. The latter is preferably inserted between bared strand wires 12b of the conductor 12 and the prong ends 221a and 221b bent about said wires in relatively opposite directions to form a substantial double-hooked anchoring connection of the terminal 221 with the conductor 12.

Fig. 9 illustrates another assembly of the current carrying members in the socket 11. Here the central current carrying member 23 is positioned to abut the exposed side of the washer 18 and is held in position under the screw head 20a instead of being located between the washer 18 and casing wall 15b as shown in Fig. 3.

It will thus be seen that there is provided devices in which the several objects of this invention are achieved and which are well adapted to meet the conditions of practical use.

As various possible embodiments might be made of the above invention, and as various changes might be made in the embodiment above set forth, it is to be understood that all matters herein set forth or shown in the accompanying drawings are to be interpreted as illustrative and not in a limiting sense.

Having thus described my invention, I

claim as new and desire to secure by Letters Patent:

1. In a lamp socket construction of the character described, a tubular insulating casing having a closed end wall, a contact shell mounted in the casing, an insulating washer engaging said shell with the end wall, a screw extending through said washer and end wall for securing the shell against displacement, a center contact secured by said screw, a cover member, said screw engaging said member for clamping the flexible conductor wires between the latter and the casing and bendable terminals integral with and extending from the center and shell contacts for engaging about and connecting with said conductor wires.

2. In a lamp socket construction of the character described, a tubular insulating casing having a closed end wall, a contact shell mounted in the casing, an insulating washer engaging said shell with the end wall, a screw extending through said washer and end wall for securing the shell against displacement, a center contact secured by said screw, a cover member, said screw engaging said member for clamping the flexible conductor wires between the latter and the casing and bendable terminals integrally formed to extend from the center and shell contacts to provide a hooked anchorage and electrical connection with the conductors.

In testimony whereof I affix my signature.
REUBEN ECKSTEIN.
